MACHINE FOR OPERATING ON COUNTERS

Charles W. Bailey, Lynn, Mass., assignor to
 Stewart Bros., a copartnership consisting of
 John Hammond Stewart and Roland A.
 Stewart, Lynn, Mass.

Application December 14, 1935, Serial No. 54,459

20 Claims. (Cl. 12—63)

This invention relates to machines for operating upon counter blanks in preparing them for use in the manufacture of shoes.

After the counter blank has been skived it is the practice to crimp the lower edge of the blank in order to facilitate the formation of the inturned heel seat flange in the molded counter. In one aspect the present invention comprises an organized machine having related skiving and crimping mechanisms cooperating in such a manner that both operations may be effected successively and automatically in a single passage of a counter blank through the machine. To this end an important feature of the invention consists in a matrix roll skiving mechanism and crimping rolls driven from a common source and so located that a skived counter blank may pass to the crimping rolls as it leaves the matrix roll and be thereupon subjected to a crimping operation throughout all or a portion of one edge. The machine of my invention is designed to include automatic feeding mechanism for delivering counter blanks successively to the matrix roll in the proper timed relation to cause the blank to be skived symmetrically at its ends. It is important therefore, that the action of the crimping rolls should also be timed with respect to this feeding mechanism, and the combination of automatic feeding mechanism with intermittently operating crimping rolls constitutes another feature of the invention.

In short counters there is no objection to crimping the entire lower edge of the blank from one end to the other because the crimped portion or zone in a short counter is all utilized in the flange. In a long shank-fitting counter on the other hand, the forward corners of the counter extend beyond the heel seat flange for an appreciable distance into the shank of the shoe. Under these conditions crimped corrugations are not only unnecessary in the forward end of the counter, but they may be positively objectionable, particularly in women's shoes in that they tend to show through the upper leather as a blemish on the otherwise smooth surface of the shoe. With these conditions in view, the present invention contemplates a crimping mechanism so controlled in its operation that the crimped zone may be limited to a predetermined portion of the counter, as for example, to an intermediate portion of its lower edge leaving the end portions of the blank smooth and uncorrugated. In this connection an important feature of the invention consists in crimping rolls arranged to be maintained either in an

operative condition of crimping pressure or in a condition wherein they are inoperative for crimping although maintaining a feeding engagement with the counter blank. Thus, the crimping rolls may be employed for feeding and crimping the blank or for merely feeding it.

The machine of my invention as herein shown is organized to perform the complete skiving operation upon successive counter blanks, and successively to perform a controlled crimping operation thereon, that is to say, to crimp a predetermined portion of the edge of the counter blank located as desired in the blank and to the desired extent. In the machine herein shown, the skiving mechanism is constructed and arranged to skive the entire lower edge of the counter blank and the crimping mechanism to form in the skived edge of the counter a crimped intermediate zone uniformly spaced from the ends of the counter. Other features of the invention consist in mechanism for advancing successive counter blanks from the skiving instrumentalities to the crimping rolls and for properly guiding and controlling the movement of the blank from one to the other. These and other features of the invention will be best understood and appreciated from the following description of a preferred embodiment thereof, selected for purposes of illustration and shown in the accompanying drawings, in which,—

Fig. 1 is a view in perspective of the machine as seen from the rear or counter-delivering side,

Fig. 2 is a sectional view of the operative parts of the machine, as seen from the side opposite that shown in Fig. 1,

Fig. 3 is a plan view of a portion of the counter feeding mechanism,

Fig. 4 is a view in perspective of the guiding device leading to the crimping rolls, and

Fig. 5 is a view in perspective of the skived and crimped counter blank.

In the machine herein illustrated I have included counter skiving mechanism of the type disclosed in my prior Patent No. 1,600,968, granted September 28, 1926, although it will be understood that the present invention is not limited to that or to any specific counter skiving mechanism. Only so much of such mechanism is herein shown as is needed for a complete understanding of the invention and for further details of construction, reference may be had to my said patent above identified. The machine frame 10 carries bearings for the main drive shaft 11 which may be rotated at suitable speed by a motor or drive pulley, not shown. 55

The frame also carries bearings for a pair of horizontal shafts, the lower shaft 18 being mounted in alignment with the drive shaft 11 and carrying a toothed lower feed roll 19, while the upper shaft 16 carries the cooperating matrix roll 17. The drive shaft 11 carries a pinion 12 meshing with a pinion 13. The latter pinion operating through back gearing, not shown, drives a pinion 15 on the feed roll shaft 18, and the pinion 15, in turn, meshes with a pinion 14 on the matrix roll shaft 16 and with the result that the feed roll 19 and matrix roll 17 are positively geared together and rotated at the same rate of speed.

The machine frame also carries a knife holder block 21 and an adjustable knife holder 22 by which a bevelled counter skiving knife 24 is accurately positioned a slight distance behind the bight of the rolls 17 and 19. The knife holder 22 is adjustably positioned upon the knife holder block by an adjusting screw 23 and the knife 24 is adjustably positioned on the knife holder by an adjusting screw 25 which acts as a positive abutment bearing against the rear edge of the knife. Unsksived counter blanks are presented successively to the feed roll 19 and matrix roll 17 by being advanced on the table 26 by an automatically acting feed slide 27 which is timed with respect to the rotation of the matrix roll so that the counter blank is symmetrically skived at its ends and along both longitudinal margins in a symmetrical manner. The end only of the feed slide 27 is shown in Fig. 2. The nature of the skiving operation, as carried out by the mechanism thus far described, is well indicated in the view of the counter blank shown in Fig. 5. After passing the edge of the knife 24 the skived blank comes out upon an apron 31 of sheet material which is pivotally supported upon a shaft 29, journaled between a pair of brackets 28 projecting upwardly from the knife holder block 21. The shaft 29 is freely rotatable and carries an idle feed roll 30, preferably rubber, which will be referred to hereinafter.

Passing now to the crimping mechanism, it will be seen that the machine frame is provided with a pair of upstanding bearing brackets 34 arranged at the rear of the machine and on either side of the path of the skived counter as it leaves the matrix roll 17. The brackets 34 are provided with a series of bearings of which the lowermost pair carries the horizontal driven shaft 35. This shaft is provided at its outer end with a sprocket 36 and is driven through a sprocket chain 37 by a driving sprocket 38 fast on the main shaft 11. It will be noted therefore that the crimping mechanism about to be described is driven positively by chain and sprocket drive in a definitely timed relation to the matrix roll 17.

The upright brackets 34 are also provided with bosses 39 in which are formed bearings for the lower crimping roll shaft 40. Mounted for rotation upon the shaft 40 is a sleeve or quill 42 and rigidly secured thereto or formed as a part thereof is the lower crimping roll 41 having a corrugated operating face. The sleeve 42 also carries a driven pinion 43 and this meshes with an idle pinion 44 carried by a stub shaft set in the left hand bracket 34. The pinion 44 is in turn driven by the driving pinion 45 fast upon the shaft 35. The lower crimping roll is therefore positively driven at all times while the matrix roll is in action.

The upper crimping roll 46 is fast to or formed

as a part of a sleeve or quill 48 which is rotatably mounted upon a shaft 47. The sleeve 48 also carries at one end a pinion 49 which meshes at all times with the pinion 43 on the lower crimping roll sleeve. The upper roll shaft 47 is journaled in vertically slotted bearings formed in the upright brackets 34 and is normally pressed downwardly through the medium of strong compression springs to maintain the crimping rolls in operative relation. During certain portions of the cycle of the machine, however, the shaft 47 is released from pressure, permitting the crimping rolls to separate and portions of the counter blank to be fed between them while in this inoperative condition without being subjected to any crimping operation. To this end the upper portion of each bracket 34 is provided with a vertical bore in which is mounted a stud 60, concave in its lower face to fit upon the end of the shaft 47, and having a downwardly extending pin 61 which passes freely through a hole in the end of the shaft 47. The pins 61 prevent rotation of the shaft while permitting it to move freely up and down. Each stud is also provided with an upwardly extending boss 62 upon which is centered the lower end of a stiff compression spring 63. The upper end of each spring 63 is centered upon a similar boss projecting downwardly from a shouldered stud or plunger 64, the upper end of the stud extending slightly above the top of the bracket member 34 in which it is mounted.

Upon the upper end of each bracket member 34 is secured a bearing and in these is journaled a horizontal shaft 66 carrying on each end a tappet arm 67 engaging at its rear end the top of one of the plungers 64. At its left-hand end, as seen in Fig. 1, the shaft 66 is provided with a downwardly extending cam arm 68 having a cam roll 69. The cam roll 69 runs upon the periphery of a cam 70 which is adjustably secured in position by a screw 71 passing through a curved slot in the cam and into the outer face of a pinion 72 which is rotatably mounted on the lower crimping roll shaft 40. The pinion 72 is driven from a driving pinion 75 keyed to the shaft 35 through an intermediate pinion 74 mounted upon a stub shaft which is journaled in the left hand bracket 34 as shown in Fig. 1.

The cam roll 69 is held at all times against the periphery of the cam 70 by the reaction of the compression springs 63 against the tappet arms 67.

The cam 70 is provided with a single long throw in its periphery and is gear driven to make one revolution to each single revolution of the matrix roll 17. While the high or throw portion of the cam is acting it holds the tappet arms 67 downwardly, in position to compress the springs 63 and hold the upper crimping roll in operative position, although permitting it to yield slightly to accommodate difference in thickness of the counter being operated upon. When, however, the low position of the cam comes around the cam arm 68 is permitted to swing in a direction to raise the tappet arms 67, thus periodically releasing the upper crimping roll so that it merely feeds that portion of the counter which happens to be beneath it and does not crimp it, but leaves it as smooth as when it passes from the skiving knife.

As will be understood the cam 70 is adjusted so that its throw becomes effective while the intermediate portion of the counter blank is passing between the crimping rolls and the tap-

pet arms are forced downwardly and held while this portion of the counter is passing. By loosening the screw 71 the cam 70 may be advanced or retarded in its position with reference to the 5 pinion 72 and thus the location of the crimped zone in the counter may be shifted and adjusted centrally or nearer to one end of the counter than the other according to the requirements of the work in hand.

10 It will be further understood that the compression springs 63 are compressed by the tappet arms while the throw portion of the cam 70 is acting, with the result that the crimping rolls are forcibly held together and are effective to 15 form a crimped zone throughout the intermediate portion of the lower edge of the counter blank as shown in Fig. 5. When the low portion of the cam 70 comes into action the springs 63 are released and permitted to elongate. The 20 upper crimping roll is thus freed from pressure and is slightly elevated by the action of the tension springs 73 which are connected to the opposite ends of the upper crimping roll shaft 47, extending upwardly therefrom to the sides of 25 the brackets in which the shaft 66 is journaled. This permits sufficient separation of the crimping rolls to terminate the crimping operation although the rolls retain feeding engagement with the counter and are effective in feeding the blank 30 fully from the machine.

In order accurately to guide the skived counter blank as it passes rearwardly from the rolls 17 and 19 a pair of spaced guide plates 52 and 53 is provided immediately behind the bight of 35 these rolls. The plate 52 is best shown in Fig. 4 as secured by screws at either end to a pair of spaced arms and constitutes with them a frame pivotally mounted to swing about the axis of the shaft 47. The lower guide plate 52 carries at one edge a stationary edge guide 54 comprising a vertically disposed plate recessed 40 at its lower edge to fit adjacent to the idle feed roll 30. It projects rearwardly behind the rear edge of the guide plate 52 and supports on its upper edge the upper guide plate 53. An adjustable edge gauge plate 55 is mounted adjacent to the stationary edge guide 54 and may be adjusted at its forward end by a pin and slot connection with the lower guide plate 52. It will 45 be understood that, as shown in Fig. 4 the guide mechanism is oppositely arranged in the machine from the position shown in Fig. 2. A guard strip 77 is arranged in position to protect the pinion 49. A vertically disposed guard strip has a hinged connection with the under face of the 50 guide plate 52 hanging downwardly.

The operation of the machine will be clear from the foregoing description, but may be briefly summarized as follows: The flat and unskived counter blanks are placed on the table 60 26 and advanced one by one by the forward movement of the feed slide 27 properly timed to meet the matrix roll 17 where the periphery thereof is shaped to force the blank downwardly for a maximum skiving operation. The advancing end of the blank is thereupon skived on a long bevel while its center portion is left substantially full thickness. The lower margin of the blank is skived on a relatively short bevel and the upper margin of the blank is skived 65 continuously on a long bevel. The rear end of the counter is skived similarly to the advancing end, all as shown in Fig. 5. As the skived counter blank leaves the matrix roll its advancing end is caught by the feed rolls 30 and 58 and

it is advanced to the crimping rolls 41 and 46 which, as already explained, are timed so as to be released and permit the advancing end of the skived blank to pass without crimping action. When the desired portion of the blank has passed 5 the rolls in uncrimped condition the throw of the cam 70 becomes effective to compress the spring 63 and establish an operative relation between the two crimping rolls which thereupon operate to impart the crimped zone to the 10 lower edge of the blank throughout a predetermined distance determined by the throw of the cam. In order to terminate the length of the crimped zone the upper crimping roll is now released and the crimping rolls maintain 15 their feeding engagement with the uncrimped end of the counter in ejecting it from the machine. The relative movement of the crimping rolls from crimping to feeding condition is not sufficient to disturb the driving engagement of 20 the pinions 43 and 49.

Having thus described my invention what I claim as new and desire to secure by Letters Patent of the United States is,—

1. A machine for operating on counter blanks, 25 including a matrix roll skiving mechanism, co-operating crimping rolls, a common actuating means for driving the matrix roll and crimping rolls, and mechanism for interrupting the effective operation of the crimping rolls independently of the skiving mechanism to cause a crimping operation to be performed on a lesser portion of the counter than the portion thereof which is skived.

2. A machine for operating on counter blanks, 35 including a matrix roll skiving mechanism constructed and arranged to skive both ends of a counter blank presented thereto, cooperating crimping rolls, a common actuating means for the skiving mechanism and crimping rolls, and 40 means for rendering the crimping rolls inoperative upon the end portions of the counter blank.

3. A machine for skiving and crimping counters, including skiving mechanism, cooperating 45 crimping rolls, driving means therefor, and automatic controlling means for throwing the crimping rolls out of operation during the passage of a counter which has been operated upon by the skiving mechanism.

4. A machine for operating on counters, comprising a pair of driven crimping rolls, means for normally pressing the rolls together to cause them to crimp a counter blank passing between them, and controlling means acting automatically 55 to release said rolls during the passage of a predetermined portion of the counter blank to relieve it from being crimped.

5. A machine for operating on counters, comprising a pair of driven crimping rolls, means 60 for normally pressing the rolls together with sufficient pressure to crimp a counter blank passing between them, and controlling mechanism for said rolls acting to release said rolls while an end portion of the counter blank is 65 passing between them.

6. A machine for operating on counters, comprising a pair of driven crimping rolls, yielding means for pressing said rolls into crimping relation, and controlling mechanism for periodically 70 releasing said rolls to such an extent as not to subject a counter passing between them to crimping but to maintain feeding engagement therewith.

7. A machine for operating on counters, com- 75

- 5 rising a pair of corrugated geared rolls, springs for yieldingly pressing one roll toward the other to cause the rolls to crimp a blank passed between the rolls, and cam operated mechanism for 5 automatically releasing said springs throughout the passage of a predetermined portion of a counter blank between the rolls.
8. A machine for operating on counters, comprising cooperating corrugated rolls geared together, driving means therefor, means for holding said rolls in a counter-crimping relation, cam operated mechanism for automatically releasing the rolls during a predetermined portion of the travel of the counter blank between them, 10 and means for adjusting the timing of such release.
9. A machine for operating on counters, comprising a skiving knife, means including a matrix roll for feeding a counter blank to the said 15 knife, and crimping rolls located at the rear of said skiving knife and arranged to crimp a skived portion of the counter blank.
10. A machine for operating on counters, comprising a skiving knife, means including a matrix roll for feeding a counter blank to said knife, driven crimping rolls located at the rear of said skiving knife, and means for feeding a skived blank from said knife to said crimping rolls to crimp a skived portion of the counter 20 blank.
11. A machine for operating on counters, comprising a skiving knife, means including a matrix roll for feeding a counter blank to said knife, driven crimping rolls located at the rear of said skiving knife, means for feeding a skived blank from the knife to the crimping rolls, and means for interrupting the crimping operation of the rolls during a predetermined interval while the skived counter blank is passing between them. 25
- 40 12. A machine for operating on counter blanks, comprising a matrix roll skiving mechanism and a pair of crimping rolls located in cooperative relation, feeding mechanism located between the two for advancing a skived blank from the skiving mechanism to the crimping rolls, and mechanism operated from a common source for driving said skiving, crimping and feeding instrumentalities.
13. A machine for operating on counter blanks, 50 comprising matrix roll skiving mechanism, means for automatically feeding a blank thereto in predetermined timed relation to the matrix roll, crimping mechanism arranged to crimp a skived blank advanced by the matrix roll, and a controlling device for the crimping mechanism op-
- 55 erating in definitely timed relation to said automatic feeding mechanism.
14. A machine for skiving and crimping counters, including skiving rolls, cooperating crimping rolls, means for simultaneously driving the same, and an automatic controlling device for throwing the crimping rolls out of operation for a predetermined interval while the skiving rolls continue in operation. 5
15. A machine for skiving and crimping counters, including matrix roll skiving mechanism constructed and arranged to bevel one edge of a counter blank, crimping rolls located behind said skiving mechanism and arranged to crimp the beveled edge of the counter, and controlling 10 means for governing the length of the crimped zone. 15
16. A machine for skiving and crimping counters, including matrix roll skiving mechanism, driven crimping rolls spaced therefrom, and a 20 driven feed roll for engaging a skived counter blank as it leaves the skiving mechanism and advancing it to the crimping rolls.
17. A machine for skiving and crimping counters, including a frame having a matrix roll 25 journaled therein, a skiving knife associated therewith, brackets secured to the frame and carrying cooperating crimping rolls, a driving shaft for said crimping rolls also journaled in the brackets, and means for driving said shaft 30 and matrix roll in positively geared relation.
18. A machine for crimping counter blanks, including crimping roll shafts, one of which is journaled for bodily movement toward and from the other, a cam mounted on one of said shafts, 35 shaft-controlling means intermittently operated by said cam, and cooperating crimping rolls mounted on said shafts.
19. A machine for skiving and crimping counters, including skiving mechanism, crimping rolls 40 spaced therefrom, and guiding means for controlling the movement of a counter blank after it leaves the skiving mechanism and directing it in accurate widthwise position to the crimping rolls. 45
20. A skiving and crimping machine comprising skiving mechanism, means for automatically feeding successive blanks thereto in timed relation, crimping mechanism spaced from said skiving mechanism, and feeding means arranged to engage each skived blank as it leaves the skiving mechanism and advance it into the effective range of the crimping mechanism. 50

CHARLES W. BAILEY. 55
